UNITED STATES PATENT OFFICE

2,073,721

AUTOMOBILE STORAGE DEVICE

Edwin M. Wheelock, Minneapolis, Minn.

Application January 18, 1930, Serial No. 421,660
Renewed July 20, 1936

17 Claims. (Cl. 214—16.1)

My invention relates to automobile storage devices, and an object in general is to improve upon prior devices of this kind. In my Patent Number 1,849,470, I have disclosed and claimed an automobile storage device which includes an elevator adapted to cooperate with alleyways on various floors of a building, a truck carried by the elevator and upon which automobiles may be placed for raising and lowering them by the elevator, and power operated mechanism for running the truck on the alleyways back and forth with relation to the elevator, and I have further disclosed and claimed an electric motor mounted on the truck for driving the same, a winding drum mounted on the elevator, and conducting cables on the winding drum connected with the motor for supplying current thereto. In my Patent Number 1,977,785, I have disclosed and claimed an automobile storage device which includes an elevator adapted to cooperate with the various floors of a building, an extensible mechanism carried by the elevator for pushing and pulling automobiles, means for connecting the extensible mechanism with automobiles, and mechanism for projecting the extensible mechanism for at least the length of an automobile and for retracting the extensible mechanism. In my Patent Number 2,047,347, I have disclosed and claimed an automobile storage device which includes an elevator adapted to cooperate with the various floors of a building, an extensible mechanism carried by the elevator for pushing and pulling automobiles, and mechanism for projecting the extensible mechanism for at least the length of an automobile in two opposite directions from the elevator and for retracting the extensible mechanism, and I have further disclosed and claimed a truck carried by the elevator and upon which the extensible mechanism is mounted in combination with power operated mechanism for running the truck on alleyways back and forth with relation to two sides of the elevator at right angles to the direction in which the extensible mechanism is capable of being projected.

Particular objects of the present invention are to provide in addition to the broad features above referred to, an improved extensible mechanism for pushing and pulling automobiles adapted to be projected for at least the length of an automobile from an elevator and to be retracted, to provide a truck carried by the elevator and upon which the improved extensible mechanism is mounted so that it may be projected therefrom and retracted, to provide means for preventing

operation of the elevator when the truck is off the elevator, and to provide means for preventing operation of the elevator when the extensible mechanism is projected outside the limits of the elevator. As shown in the particular embodiment herein disclosed, the extensible mechanism includes a plurality of slides with which a flexible element is associated and adapted to be driven in such manner that the extensible mechanism may be projected to the desired extent from either of two opposite sides of the elevator, the slides when in neutral or retracted position being nested together within the periphery of the elevator. By mounting the extensible mechanism upon a truck which is capable of being driven in opposite directions from the elevator and at right angles to the direction of projection movement of the extensible mechanism, one elevator may be made to serve a large amount of floor space having stalls extending out in all directions from the elevator. This is a matter of particular importance in connection with buildings having a small number of floors and spreading out over considerable ground.

The full objects and advantages of my invention will appear in connection with the detailed description thereof, and the novel features of my inventive idea will be particularly pointed out in the claims.

In the accompanying drawings which illustrate one of the forms in which my invention may be embodied,—Fig. 1 is a top plan view in which a truck is shown in position on an elevator. Fig. 2 is a fragmentary plan view showing the slides which appear in Fig. 1 on an enlarged scale. Fig. 3 is a view in vertical section on the line 3—3 of Fig. 1 on an enlarged scale. Fig. 4 is a view in vertical section on the line 4—4 of Fig. 1 on an enlarged scale. Fig. 5 is a view in vertical section on the line 5—5 of Fig. 1 on an enlarged scale. Fig. 6 is a view in horizontal section on the line 6—6 of Fig. 5. Fig. 7 is a view in section through a slide member showing the manner in which different stretches of a cable cross each other. Fig. 8 is a view in vertical section on the line 8—8 of Fig. 6. Fig. 9 is a detail view showing the manner in which rollers are used to support the slide members. Fig. 10 is a fragmentary perspective view showing the construction of sheet metal members which carry the slides. Fig. 11 is a diagrammatic view showing the position of the stretches of a cable when the slides are all in place on the elevator. Fig. 12 is a view showing the position of the stretches of the cable when the slides are

projected to one side. Fig. 13 is a view showing the position of the stretches of the cable when the slides are projected to the other side. Fig. 14 is a sectional view of a switch taken on the line 5 14—14 of Fig. 15. Fig. 15 is a view taken in section on line 15—15 of Figs. 1 and 14. Fig. 16 is a wiring diagram showing connections for switches. Fig. 17 is a view in section on line 10 17—17 of Figs. 1 and 18. Fig. 18 is a view in section on line 18—18 of Fig. 17. Fig. 19 is a view in section on the line 15—15 of Fig. 4. Figs. 22 to 25 are wiring diagram views.

Referring to the construction shown in the drawings, the numeral 24 designates an elevator platform which may be raised and lowered in any 20 well known manner so as to register substantially with the floors of a storage garage or building, one of the floors being indicated by the numeral 25. The floors of the building adjacent the elevator are preferably provided with 25 slideable fire doors 26, one for each of the four sides of the elevator. A truck indicated at 28 has small wheels 30 at the four corners thereof so that it may be run upon and off the elevator platform 24. For the purpose of guiding the truck along 30 the alleyways on the floors, tracks or ways 32 may be provided and these tracks or ways may be of the nature disclosed in my prior application Serial Number 91,080 filed February 27, 1926, in which both metal tracks and grooves in the floor 35 are disclosed. It will be understood that similar tracks for the truck are provided on the elevator platform 22, these tracks being indicated at 34. At least two housing members 36 and 38 spaced from each other are secured to the truck 28, these 40 two members taken together being of such width that they may be straddled by the wheels of an automobile as will be understood from Fig. 1 in which the numeral 40 designates the wheels of an automobile. While this figure shows only 45 one pair of housing members, it will be understood from Figs. 3 and 4 that if the elevator is of sufficient size, two or more pairs of the housing members may be mounted thereon in order that two or more automobiles may be carried 50 at one time by the elevator. An extensible mechanism which will shortly be referred to in detail is mounted between the pair of housing members 36 and 38, the extensible mechanism being so constructed that it may be projected from the 55 elevator for at least the length of an automobile.

Mounted on the truck in any convenient position such as shown in Fig. 1, there is a reversible electric motor 42 whose shaft carries a gear 44 meshing with a gear 46 secured to a shaft 48 60 upon which two of the truck wheels 30 are secured so that by operating the motor 42 in one direction or the other, the truck may be moved off from and on to the elevator. Mounted in the housing member 38 as shown in Fig. 4, there is a reversible electric motor 50 whose shaft carries a gear 52 meshing with a gear 54 secured to one end of a shaft 56 which is provided with a worm 60 which meshes with a worm gear 62 formed on the periphery of a sheave or drum 64 as will 65 be understood in connection with Fig. 3. The sheave 64 is rotatably mounted in horizontal position on a support 66 secured to the truck midway between the housing members 36 and 38. As will be understood from Figs. 3 and 4, a number of pairs of supports 68 and 70 extend across 75

the truck, being secured thereto in spaced relation in the space between the housing members 36 and 38, and pairs of rollers 72 and 74 are mounted on these supports. The pairs of rollers 72 and 74 serve to support a sheet metal structure which is shown in plan in Fig. 19. This structure consists of side strips 76 and 78 spaced from each other and connected by end cross pieces 79 and an intermediate cross piece 80 while intermediately positioned between the side 10 strips 76 and 78 there are pairs of angle bars 81 and 82, the cross pieces being offset upwardly as will be understood from Fig. 10 so as to provide portions 83 which fit together with the angle bars 81 and 82. A sheet metal structure shown 15 in plan in Fig. 20 is slidably mounted on and is narrower than the sheet metal structure just described. This narrower sheet metal structure consists of end cross pieces 88 and an intermediate cross piece 90, these cross pieces being 20 offset upwardly as will be understood from Fig. 10 so as to provide portions 92 which fit slidably over the offset portions 83. As will be understood from Fig. 9 the floor 25 has secured thereto, supports 94 in which are mounted rollers 96 upon 25 which the bars 81 and 82 are adapted to run. A central slide member 98 rests slidably upon the cross pieces 88 and 90, this slide being in the form of a hollow beam having a longitudinal slot in its lower side to receive the offset portions 30 92. At the two sides of the slide member 98, there are a pair of slides 100 and 102 which are in the form of I-beams and are secured to the cross pieces 88 and 89 as will be understood from 35 Fig. 20. At the outer sides of the slide members 100 and 102, there are a pair of slide members 104 and 106 which are in the form of I-beams and are secured to longitudinal strips 76 and 78 respectively as will be understood from Fig. 19. It is apparent, therefore, that the slide members 40 100 and 102 will travel in unison with each other and that the slide members 104 and 106 will travel in unison with each other. As will appear later, the central slide 98 has a portion only of 45 its projection movement independently of the slide 100 and 102 while the slides 100 and 102 have a portion only of their projection movement independently of the slides 104 and 106. As will be understood from Figs. 5, 7, 11, 12 and 13 the center slide 98 has a pulley 108 mounted 50 at one end thereof and a pulley 108' mounted at the other end thereof. The two intermediate slides 100 and 102 have two pulleys mounted at each end thereof, one above the other. For the slide 100, the two pulleys at one end thereof are 55 designated 110 and 112 while the two pulleys at the other end thereof will be referred to as 110' and 112', it being understood that the pulley 112 is below the pulley 110 as shown in Figs. 3 and 4 and that the pulley 112' is below the pulley 110'. 60 For the slide 102, the two pulleys at one end thereof are designated 114 and 116 while the two pulleys at the other end thereof will be referred to as 114' and 116', it being understood that the pulley 116 is below the pulley 114 and that the pulley 116' is below the pulley 114'. The two outer slides 104 and 106 also have two pulleys 65 mounted at each end thereof. For the slide 104, the two pulleys at one end thereof are designated 118 and 120 while the two pulleys at the other end thereof will be referred to as 118' and 120', it being understood that the pulley 120 is below the pulley 118 and that the pulley 120' is below the pulley 118'. For the slide 106, the two pulleys 70 at one end thereof are designated 122 and 75

124 while the two pulleys at the other end thereof will be referred to as 122' and 124', it being understood that the pulley 124 is below the pulley 122 and that the pulley 124' is below the pulley 122. By referring to Figs. 6, 11, 12 and 13, it will be understood that one end of a flexible element such as a cable 126 is secured to a projection 128 carried by the housing member 36. From the projection 128, this cable passes around the various pulleys in the following order: 118, 118, 110', 110, 108', 114, 114', 122, 122' then in engagement with direction and supporting pulleys 130, 132, 134, and 136 carried by the housing 38, then around the sheave 64 and in engagement with direction pulleys 138, 140 and 142 and then around the pulleys 120, 112', 112, 108, 116', 116, 124' and 124 with the other end of the cable passing around a pulley 144 and secured to one end of a stiff spring 146 whose other end is secured to a projection 148 carried by the housing member 38. It will be apparent that the spring 146 is one form of device which may be provided for taking up slack in the cable and that the sheave or driving member 64 will be of such character that slipping of the cable thereon is prevented.

In order to provide for the crossing of the portions constituting different stretches of the cable 126, the slides are furnished with slots 150 such as shown in Fig. 7 in connection with the slide 106. 30 When the slides are in nested condition on the elevator or on the truck when the latter is off the elevator, the cable assumes the position shown in Fig. 7. On causing the motor 50 to drive the sheave 64 in one direction, the cable 35 will be brought into the position shown in Fig. 12 and thereby project the slides of the extensible mechanism toward the left while if the motor is reversed to drive the sheave 64 in the opposite direction, the cable will be brought into the position shown in Fig. 13 and thereby project the extensible mechanism toward the right. In the embodiment shown, the extensible mechanism consists of three extensible members, one of which is the central slide 98, another of which is 40 made up of the two intermediate slides 100 and 102, and the third of which is made up of the two outside slides 104 and 106. Since each of the extensible members is adapted to move an automobile a little more than the distance of 45 its length, it will be understood that three stalls arranged in tandem and extending away from the elevator may be filled while by running the truck off the elevator, a large number of stalls may be filled by the use of a single extensible 50 mechanism. Means is provided to prevent the slide members of the extensible mechanism from becoming separated from each other when they are extended. Such means is shown in Fig. 2. When the central slide 98 is projected its full 55 relative distance toward the left, a stop 152 carried thereby comes into engagement with a stop 154 carried by the slide 100 and when it is projected its full relative distance toward the right, a stop 156 carried thereby comes into engagement with a stop 158 carried by the slide 102. When 60 the intermediate slides 100 and 102 are projected their full relative distance toward the left, a stop 160 carried by the slide 100 comes into engagement with a stop 162 carried by the slide 104, and when the intermediate slides 100 and 65 102 are projected their full relative distance toward the right, a stop 164 carried by the slide 102 comes into engagement with a stop 166 carried by the slide 106. When the outside slides 70 75 104 and 106 are projected their full relative dis-

tance toward the left, a stop 168 carried by the slide 104 comes into engagement with a stop 170 carried by the housing 36 and when the outside slides 104 and 106 are projected their full relative distance toward the right, a stop 172 carried by the slide 106 comes into engagement with a stop 174 carried by the housing 38.

It is preferable that the sections of the telescoping slides shall be caused to always move outwardly in a predetermined order. Mechanism for accomplishing this result is shown in Figs. 17 and 18. When the slides are in nested condition, a spring-pressed bolt 176 carried by the housing 36 engages in a notch in the slide 104, a spring-pressed bolt 178 carried by the slide 100 engages in a notch in the slide 104 while a spring-pressed bolt 180 carried by the central slide 98 engages in a notch in the slide 100. When the projection movement is started, all of the slides will move outwardly together due to the fact that the engaging end of the bolt 176 is rounded and does not project very far into its notch. The combined movement of the slides is sufficient to carry an automobile into the first stall which, of course, is the one adjacent the elevator. If the projecting movement is continued, the intermediate slides 100 and 102 will next move outwardly, it being noted that the engaging end of the bolt 178 is somewhat sharp and extends somewhat further into its notch than is the case with the bolt 176. This movement is sufficient to carry an automobile into the second stall which is further out. The center slide 98 will be the last to move out due to the fact that the engaging end of the bolt 180 is sharper. This last movement of the slides when employed will cause an automobile to move into the third stall. It is obvious that by increasing the number of slides, the number of stalls which may be filled in tandem relation will be correspondingly increased.

It will be understood that some means must be provided for causing the slides to be connected with the automobile which is to be pushed off the elevator or truck and also to be connected with an automobile which is to be pulled on to the elevator or truck. For this purpose, a rotatable shaftlike member 182 is mounted in bearings 184 and 186 carried by the central slide 98. The shaft 182 is provided with at least two outstanding pins 188 and 190 so spaced from each other as to be capable of straddling the axle A of an automobile when they are moved into position extending upwardly as shown in Fig. 5. In order to give rotative movement to the shaft 182, for engaging and releasing these pins with relation to the axle, the shaft is provided with a bevel gear 192 which meshes with a bevel gear 194 which is integral with or secured to a pinion 196. This pinion meshes with a rack 198 carried for sliding movement by the core 200 of a solenoid 202 so that the shaft 182 will be given rotative movement in one direction when the solenoid is energized and will be given rotative movement in the opposite direction when the solenoid is deenergized. In order to supply current to the coil of the solenoid regardless of the position of the slide 98, a cord 204 is connected to said coil and this cord after passing around direction pulleys 206, 208, 210 and 212 winds upon a reel 214 which permits the cord 204 to be drawn out when the slide is extended.

As shown in Fig. 4, current is supplied by a feed line 216 to a conducting cable 218 which is wound on a reel 220 mounted on the elevator plat-

form 24, the outer end of this cable being connected to a contact device 222 carried by the truck housing 38. From the contact device 222 a wire 224 leads to a spring finger 226 mounted on the truck. When the truck is in place upon the elevator, the spring finger 226 engages a spring finger 228 carried by the elevator platform. A wire 230 connected with the finger 228 supplies current for operating the elevator as will be understood from Fig. 16. As soon as the truck starts to move in either direction off the elevator, the contact between the fingers 226 and 228 is broken so that the elevator cannot be started when the truck is off the elevator. As shown in Figs. 14, 15, and 16, the wire 224 includes two spring fingers 232 and 234 which are secured to the truck housing 38 in spaced relation to each other to constitute members of a switch. A bridge member 236 secured to the slide member 105 completes the circuit between the fingers 232 and 234 when the extensible mechanism is in neutral or nested position upon the elevator. As soon as the extensible mechanism starts to move out in either direction, the contact between the fingers 232 and 234 is broken so that the elevator cannot be started unless the extensible mechanism is in its neutral retracted position.

As shown in Figs. 4 and 21, the outer end of the shaft 58 which drives the sheave 64, has a screw threaded portion 238 which carries a nut 240 which is thereby caused to move back and forth as the extensible mechanism is extended and retracted. Adjacent the screwthreaded portion 238, a solenoid 242 is secured to the truck housing 36. The solenoid core 244 is extended at both ends of the solenoid and at one end is surrounded by a coiled spring 246 which is interposed between a fixed abutment 248 and a collar 250 secured to the core so that when the solenoid is deenergized, the spring 246 tends to move the core toward the right into the position shown in Fig. 23. Adjacent the collar 250, one end of an arm 252 is pivotally attached to the core 244, this arm being intermediately pivoted at 254 and its other end carrying a contact member 256 which in the position of Fig. 23 engages a fixed contact member 258. The other end of the core 244 insulatively carries a contact member 260 which in the position shown in Figs. 21 and 22 bridges two fingers 262 and 264 spaced from each other to form members of a switch. Adjacent the contact member 260, one end of an arm 266 is pivotally attached to the core 244, this arm being intermediately pivoted at 268 and its other end carrying a contact member 270 which in the position of Figs. 21 and 22 engages a contact member 272 and in the position of Fig. 23 is disengaged therefrom. The two contact members 256 and 270 are joined by a wire 273. As shown in Fig. 1, an operator's seat 274 is placed in suitable position on the truck adjacent a switch stand 276 on which is placed a switch which as shown in Figs. 22, 23, 24 and 25 includes a pivoted arm 278 adapted to be engaged with either one of two contacts 280 and 282. Also mounted on the switch stand, there is a double throw switch which includes the arms 284 and 286. The arm 284 is pivotally attached to a contact 288 and is adapted to be engaged either with a contact 290 as shown in Fig. 22 or with two contacts 292 and 294 at the same time, as shown in Fig. 23. The arm 286 is pivotally attached to a contact 296 and is adapted to be engaged either with the contact 292 as shown in Fig. 2 or with the contact 290 as shown in Fig. 23. The pivoted end 75 of the arm 286 carries three branches 298, 300 and

302. In the position of Fig. 22, the branch 298 engages a contact 304 and the branch 302 engages a contact 306 while in the position of Fig. 23, the intermediate branch 300 engages the contact 306. The manner in which the various contacts are wired up will be understood in connection with the following description of the operation of this portion of the device. In Fig. 22, the extensible mechanism has been projected for its full length toward the right and has been automatically stopped in a manner which will soon be apparent and the operator has just thrown the switch members 284 and 286 from the position shown in Fig. 23 into that shown in Fig. 22 in order to start the retracting movement toward the left. Current now flows through the supply wire 308, the solenoid coil, a wire 310, contacts 262, 266, and 264, a wire 312, the contact 280, the switch member 278 and a wire 314 to the return wire 316, thereby energizing the solenoid 242 and holding the core 244 toward the left in opposition to the tension of the spring 246. At the same time, current flows from the supply wire 308 through a wire 318, the wire 273, contacts 270 and 272, a wire 320, contact 304, and branch 298 to the contact 296. Here the current divides, a portion of it passing through the switch member 286, contact 292, the field winding 322, of the motor, and wire 324 to the return wire 316. The other portion of the current passes from the contact 296 through the branch 302, contact 306, a wire 326, the armature winding 328 of the motor 50, a wire 330, contact 288, switch member 284, contact 290 and a wire 332 to the return wire 316. The passage of current through the coil 328 causes the motor 50 to turn in the proper direction to retract the extensible mechanism and at the same time feed the nut 240 toward the left. It is obvious that the operator may at any time before the nut 240 reaches the arm 252, throw the switch members 284 and 286 and thereby stop the motor. In Fig. 23, the extensible mechanism has been projected for its full length toward the left and has been automatically stopped on account of the nut 240 having engaged the arm 252 and move the solenoid core toward the right, thereby breaking the connection between the contacts 270 and 272. At the same time, the bridge 260 has been automatically moved from engagement with the contacts 262 and 264. In the position shown in Fig. 23, the operator has just thrown the switch members 284 and 286 from the position shown in Fig. 22 in order to start the retracting movement toward the right. Current now flows through the supply wire 308, the wire 318, the wire 273, contacts 256 and 258, a wire 334, the contact 294 and the switch member 284, it being noted that this switch member is long enough to engage the two contacts 292 and 294. At the contact 292, the current divides, a portion of it passing through the field winding 322 and the wire 324 to the return wire 316. The other portion of the current passes from the contact 292 through the switch member 284, contact 288, the armature 328 in the reverse direction from that shown in Fig. 22, the wire 326, contact 306, the branch 300, contact 298, the switch member 286, the contact 290, and the wire 332 to the return wire 316. It will be noted that the motor 50 is rotated in reverse direction from that in Fig. 22. It is obvious that the operator may at any time before the nut 240 reaches the arm 256 throw the switch members 284 and 286 and thereby stop the motor. The extensible members may thus be stopped in nested condition on the elevator or they may be stopped in such position that an auto- 75

mobile will be moved into either the first, the second, or the third stall extending out from the elevator. This capability of operation exists both for the right and left hand movement of the extensible mechanism. Whenever the movement of the extensible mechanism has thus been stopped, such mechanism may be immediately retracted without being extended for its full length. For instance, if the operator wishes to reverse in one direction, he throws the switch member 278 from the position of Fig. 22 into that of Fig. 24 so that with the bridge 260 in the position of Fig. 23, current will flow through the solenoid 242, a wire 336, the contact 282, the switch member 278, and the wire 314, to the return wire 316. The energization of the solenoid 242 will pull the core 244 from the position of Fig. 23 into that of Fig. 22 against the tension of the spring 246 so that the bridge member 260 is caused to bridge the contacts 262 and 264. If he wishes to reverse in the other direction, then the switch member 278 is thrown into the position shown in Fig. 25.

The operation and advantages of my invention have in large measure already been set forth. In the use of the device, an automobile on the ground floor is brought close to the elevator shaft and the elevator platform is lowered so as to bring the truck thereon into register with the ground floor unless the elevator is already in lowered position.

30 The extensible mechanism is then moved out to the proper extent and by energizing the solenoid 262, the pins 188 and 190 will be caused to straddle the axle A of the automobile so that the automobile can be pulled upon the truck by retracting 35 the extensible mechanism in the manner previously set forth. When the automobile has been taken up to the desired floor, the extensible mechanism may be operated in either of two opposite directions to push the automobile into any 40 one of the first, second or third stalls extending out from the elevator. When stalls along the alleyways are to be filled, the truck may be moved off the elevator in either of two directions to any desired place on the alleyways, the movement of the 45 truck being at right angles to the line in which the extensible mechanism operates, and then by operating the extensible mechanism, the various stalls may be filled, it being understood that the mechanism regardless of whether it operates directly 50 out from the elevator or from the truck when off the elevator may be extended for the distance of at least three stalls.

I claim:

1. In an automobile storage device for buildings 55 having a plurality of floors, the combination of an elevator, extensible mechanism consisting of a plurality of slides carried by said elevator for pushing and pulling automobiles, and mechanism for projecting said extensible mechanism for at least the length of an automobile from said elevator and for retracting said mechanism.

2. In an automobile storage device for buildings having a plurality of floors, the combination of an elevator, extensible mechanism consisting of a plurality of slides carried by said elevator for pushing and pulling automobiles, and mechanism for projecting said extensible mechanism for at least the length of an automobile from said elevator in two opposite directions with relation thereto 65 and for retracting said mechanism.

3. In an automobile storage device for buildings having a plurality of floors, the combination of an elevator, extensible mechanism consisting of a plurality of slides carried by said elevator for pushing and pulling automobiles, mechanism for 70

projecting said extensible mechanism for at least the length of an automobile from said elevator and for retracting said mechanism, a rotatable member carried by said extensible mechanism, projections on said member, and mechanism for giving said member rotative movement for engaging and disengaging said projections with relation to the axle of an automobile. 5

4. In an automobile storage device for buildings having a plurality of floors, the combination of an elevator, slidable mechanism carried by said elevator for pushing and pulling automobiles, said slidable mechanism consisting of a plurality of interconnected relatively movable parts adapted for right line movement and nested together on the elevator in their retracted position, a flexible element connected with said slidable mechanism for projecting and retracting the latter, and driving mechanism for said flexible element adapted to be operated in opposite directions. 10

5. In an automobile storage device for buildings having a plurality of floors, the combination of an elevator, extensible mechanism consisting of a plurality of telescoping slides carried by said elevator for pushing and pulling automobiles, and mechanism for projecting and retracting said slides one after the other. 15

6. In an automobile storage device for buildings having a plurality of floors, the combination of an elevator, extensible mechanism consisting of a plurality of telescoping slides carried by said elevator for pushing and pulling automobiles, and mechanism for projecting and retracting said slides one after the other in predetermined order. 20

7. In an automobile storage device for buildings having a plurality of floors, the combination of an elevator, extensible mechanism consisting of a plurality of telescoping slides carried by said elevator for pushing and pulling automobiles, pulleys carried by said slides, a flexible element stretched around said pulleys for projecting and retracting said slides, and driving mechanism for said flexible element adapted to be operated in opposite directions. 25

8. In an automobile storage device for buildings having a plurality of floors, the combination of an elevator, extensible mechanism consisting of a plurality of telescoping slides carried by said elevator for pushing and pulling automobiles, a flexible element stretched around said pulleys for projecting and retracting said slides with relation to two sides of the elevator, and driving mechanism for said flexible element adapted to be operated in opposite directions. 30

9. In an automobile storage device for buildings having a plurality of floors, the combination of an elevator, extensible mechanism carried by said elevator consisting of a central slide and slides arranged at the opposite sides thereof in pairs for pushing and pulling automobiles, and mechanism for projecting and retracting said central slide and said pairs one after the other. 35

10. In an automobile storage device for buildings having a plurality of floors, the combination of an elevator, a truck adapted to be carried by said elevator, a reversible motor carried by said truck for driving the latter off and on to said elevator, extensible mechanism consisting of a plurality of slides mounted on said truck for pushing and pulling automobiles, and a reversible motor carried by said truck for projecting and reTRACTING said slides. 40

11. In an automobile storage device for buildings having a plurality of floors, the combination of an elevator, extensible mechanism carried by

75

said elevator for pushing and pulling automobiles, a movable member carried by said extensible mechanism adapted to be engaged with and disengaged from an automobile, a solenoid for 5 operating said movable member, and means for energizing and de-energizing said solenoid.

12. In an automobile storage device for buildings having a plurality of floors, the combination of an elevator, extensible mechanism carried by 10 said elevator for pushing and pulling automobiles, a rotatable member carried by said extensible mechanism and adapted by its rotative movement to be engaged with and disengaged from an automobile, a solenoid, connections between the core 15 of said solenoid and the said rotatable member for rotating the latter, and means for energizing and deenergizing said solenoid.

13. In an automobile storage device for buildings having a plurality of floors, the combination 20 of an elevator, extensible mechanism carried by said elevator for pushing and pulling automobiles, said extensible mechanism consisting of a plurality of interconnected relatively movable parts adapted for right line movement and nested to- 25 gether on the elevator in their retracted position, mechanism for projecting said extensible mechanism, and means for automatically stopping said extensible mechanism when projected to its full extent.

30 14. In an automobile storage device for buildings having a plurality of floors, the combination of an elevator, extensible mechanism carried by said elevator for pushing and pulling automobiles, said extensible mechanism consisting of a plu- 35 rality of interconnected relatively movable parts adapted for right line movement and nested together on the elevator in their retracted position, mechanism for projecting said extensible mechanism, means for stopping said extensible mecha- 40 nism at any point in its projection movement, and means for thereupon causing said extensible mechanism to be retracted.

45 15. In an automobile storage device for buildings having a plurality of floors, the combination of an elevator, extensible mechanism car-

ried by said elevator for pushing and pulling automobiles, said extensible mechanism consisting of a plurality of interconnected relatively movable parts adapted for right line movement and nested together on the elevator in their re- 5 tracted position, mechanism for projecting said extensible mechanism in two opposite directions from said elevator, means for stopping said extensible mechanism at any point in its projec- 10 tion movement, and means for thereupon caus- 15 ing said extensible mechanism to be retracted.

16. In an automobile storage device for buildings having a plurality of floors, the combination of an elevator, a truck adapted to be carried by 15 said elevator, mechanism for moving said truck off and on to the elevator, extensible mech- 20 anism mounted on said truck for pushing and pulling automobiles, said extensible mechanism consisting of a plurality of interconnected relatively movable parts adapted for right line move- 25 ment and nested together on the elevator in their retracted position, mechanism for project- 30 ing said extensible mechanism from said truck, means for stopping said extensible mechanism at any point in its projection movement, and 35 means for thereupon causing said extensible mechanism to be retracted.

17. In an automobile storage device for buildings having a plurality of floors, the combination of an elevator, a truck adapted to be carried by 30 said elevator, mechanism for moving said truck off and on to said elevator with relation to two opposite sides thereof, extensible mechanism mounted on said truck for pushing and pulling 35 automobiles, said extensible mechanism consist- 40 ing of a plurality of interconnected relatively movable parts adapted for right line movement and nested together on the elevator in their re- tracted position, mechanism for projecting said extensible mechanism from said truck for every 45 position thereof, means for stopping said exten- sible mechanism at any point in its projection movement, and means for thereupon causing said extensible mechanism to be retracted.

EDWIN M. WHEELOCK. 45
